Patented May 6, 1924.

1,493,111

UNITED STATES PATENT OFFICE.

ROBERT E. DIVINE, OF CINCINNATI, OHIO.

DETERGENT AND PROCESS OF MAKING THE SAME.

No. Drawing.

Application filed August 11, 1920. Serial No. 402,824.

To all whom it may concern:

Be it known that I, ROBERT E. DIVINE, a citizen of the United States, residing at Cincinnati, in the county of Hamilton and 5 State of Ohio, have invented certain new and useful Improvements in Detergents and Processes of Making the Same, of which the following is a specification.

My invention relates to the production of 10 a detergent compound from alkali metal sulfonates and particularly from alkali metal sulfonates obtained according to the methods described in U. S. patents to Petroff No. 1,233,700 dated July 17, 1917, and 15 Humphreys No. 1,286,179 dated Nov. 26, 1918.

Patents 1,286,179 and 1,233,700 disclose processes wherein a hydrocarbon oil after treatment with fuming sulfuric acid and 20 separation of the resulting acid sludge is treated to recover the sulfonic acids remaining in the oil. According to Patent No. 1,286,179 the oil is first treated with alkali which combines with the sulfonic acids 25 forming alkali metal sulfonates which then are dissolved from the oil by washing with an organic solvent such as methyl or ethyl alcohol or acetone. According to Patent No. 1,233,700 the sulfonic acids are dissolved 30 from the separated oil by means of an organic solvent such as methyl or ethyl alcohol or acetone and the solution of sulfonic acids treated with alkali to form alkali metal sulfonates. In these processes organic 35 solvents of relatively low concentration say 30 to 50% are employed. In applying the above described processes to American petroleum it has been found that the resulting sulfonic acid product is not sufficiently soluble in water to be used readily 40 for detergent purposes.

The product obtained by the application of the Humphreys and Petroff processes when applied to American petroleum contains 45 considerable quantities of free oil to which the sticky or gummy and water insoluble characteristics of the product are attributed.

The object of my invention is to refine the 50 above described oil-containing sulfonic acid product by removing therefrom the free oil or a sufficient proportion thereof to render the product readily soluble in water and as a result thereof readily usable for detergent 55 purposes.

The alkali metal sulfonates and free oil

in the product produced by Humphreys' and Petroff's processes cannot be separated by extraction with solvents such as naphtha because the entire product is soluble in such 60 solvents.

My process of refining is as follows:

The alkali metal sulfonate product containing free oil is completely freed from water and then treated with relatively 65 strong organic solvent such as methyl or ethyl alcohol or acetone for instance ethyl alcohol of from 70 to 100% concentration. For example, the semi-liquid or viscous product obtained by the Petroff process is 70 freed from water by boiling in a steam jacketed vessel until substantially all of the water is removed. The dry product thus obtained then is treated with 70 to 100% alcohol by mixing and thorough stirring. The 75 mixture is allowed to settle with the formation of two layers, one containing an alcoholic solution of alkali metal sulfonates and the other layer comprising oil containing a small amount of alkali metal sulfonate. The 80 two layers are separated by decantation or otherwise and the alcoholic solution is distilled to recover the alcohol, the residual material being a neutral alkali metal sulfonate compound, substantially free from 85 oil and sufficiently soluble in water to enable it to be employed directly for detergent purposes. The product is semi-pasty, similar in physical characteristics to 90 soft soap and possesses high detergent properties. Being free from uncombined alkaline or acid constituents and having good detergent properties toward greases and other foreign matter or dirt ordinarily present in soiled fabrics it constitutes an excellent 95 cleansing medium for the most delicate fabrics.

The alkali metal sulfonates produced according to Humphreys' process may be refined in the same manner as that described 100 above and with similar results.

In the separation of the alcoholic solution of alkali metal sulfonates from oil as above described the oil layer retains appreciable quantities of alkali metal sulfonates which may be recovered by further treatment of the oil by extraction with strong alcohol and separation of the alcoholic solution.

The alkali metal sulfonates above referred 110 to are, ordinarily, the sodium sulfonates.

My process contemplates broadly the

treatment of alkali metal sulfonate products recovered from petroleum oils for the removal therefrom of all or a substantial portion of their free oil content and the production of a readily water soluble product and is not limited to any particular method of production or source of the free oil containing material.

I claim:

- 5 1. Process of refining alkali metal sulfonates obtained from hydrocarbon oils by treating such oils with sulfuric acid, separating the oil from acid sludge, extracting said oil with organic solvent which is insoluble in said oil, treating the solution with alkali, and separating said solvent from the solution which comprises freeing said sulfonates from water, extracting the dried residue with an organic solvent soluble in water, separating the resulting solution from oil and separating the organic solvent from the separated solution.
- 10 2. Process for refining alkali metal sulfonates derived from petroleum oils and containing free oil which comprises freeing said sulfonates from water, and extracting said dried sulfonates with concentrated water soluble organic solvent whereby said sulfonates are separated from free oil.
- 15 3. Process for refining alkali metal sulfonate material containing free oil which

comprises freeing said material from water dissolving the sulfonate content of said material with alcohol of from 70 to 100%, separating the alcoholic solution of sulfonates from said oil, and recovering said sulfonates from said alcoholic solution by evaporation.

4. Process for refining alkali metal sulfonates contained in material comprising free oil and water which comprises drying said material, dissolving said sulfonates in said dried material in a highly concentrated solution of ethyl alcohol, separating the resulting alcoholic solution from oil and evaporating said solution.

5. Process of making a readily water soluble detergent comprising alkali metal sulfonates from alkali metal sulfonate material derived from petroleum hydrocarbon oil and containing free oil and water, which comprises removing water from said material by evaporation at elevated temperature, extracting the dried material with concentrated alcohol, separating the resulting alcoholic solution from oil and evaporating said solution whereby alkali metal sulfonates substantially free from oil are produced.

In testimony whereof, I affix my signature.

ROBERT E. DIVINE.
